US0D1066286S

(12) **United States Design Patent** (10) **Patent No.:** **US D1,066,286 S**
(45) **Date of Patent:** **** Mar. 11, 2025**

(54) **EARPHONES**

(71) Applicant: **Apple Inc.**, Cupertino, CA (US)

(72) Inventors: **Christopher Wiita**, West Hollywood, CA (US); **Robert Boyd**, Los Angeles, CA (US); **Duy P. Le**, Venice, CA (US); **Carlos M. Santana**, Granada Hills, CA (US)

2,719,523 A 10/1955 Von
2,739,660 A 3/1956 French
3,195,392 A 7/1965 Allen
3,213,679 A 10/1965 Lebow

(Continued)

(73) Assignee: **Apple Inc.**, Cupertino, CA (US)

(**) Term: **15 Years**

(21) Appl. No.: **29/930,700**

(22) Filed: **Mar. 1, 2024**

FOREIGN PATENT DOCUMENTS

CA	173260	9/2017
CA	190012	5/2021

Primary Examiner — Paula Allen Greene

(74) *Attorney, Agent, or Firm* — Sterne, Kessler, Goldstein & Fox P.L.L.C.

(57) **CLAIM**

The ornamental design for earphones as shown and described.

DESCRIPTION

FIG. 1 is a front view of earphones showing the claimed design;

FIG. 2 is a rear view thereof;

FIG. 3 is a top view thereof;

FIG. 4 is a bottom view thereof;

FIG. 5 is a right side view thereof; and,

FIG. 6 is a left side view thereof.

The broken lines in the figures show portions of the earphones that form no part of the claimed design.

1 Claim, 6 Drawing Sheets
